UNITED STATES PATENT OFFICE.

WILLIAM J. SCHWERIN, OF SAN FRANCISCO, CALIFORNIA.

DESIGN FOR A GLASS SWITCH PLATE.

Application filed February 11, 1925. Serial No. 12,347. Term of patent 3½ years.

To all whom it may concern:

Be it known that I, WILLIAM J. SCHWERIN, sign,
a citizen of the United States of America,
residing at San Francisco, in the county of
San Francisco and State of California, have
invented a new, original, and ornamental
Design for a Glass Switch Plate, of which
the following is a specification, reference
being had to the accompanying drawings,
forming a part thereof.

Figure I is a front elevation of my de-
sign,

Figure II is an end view of the same,
and

Figure III is a cross-section through the
design.

I claim:—

The ornamental design for a glass switch
plate, substantially as shown.

WILLIAM J. SCHWERIN.
